W. WHELAN.
ADJUSTABLE PIPE WRENCH.
APPLICATION FILED AUG. 6, 1918.

1,401,931.

Patented Dec. 27, 1921.

Inventor:
William Whelan,
By: S. Singer, Atty.

UNITED STATES PATENT OFFICE.

WILLIAM WHELAN, OF PLYMOUTH, ENGLAND.

ADJUSTABLE PIPE-WRENCH.

1,401,931.

Specification of Letters Patent. Patented Dec. 27, 1921.

Application filed August 6, 1918. Serial No. 248,601.

(GRANTED UNDER THE PROVISIONS OF THE ACT OF MARCH 3, 1921, 41 STAT. L., 1313.)

To all whom it may concern:

Be it known that I, WILLIAM WHELAN, a subject of the Kingdom of Great Britain, residing at 2 Moor View, Mutley, Plymouth, Devon, England, mining and marine engineer, have invented certain Improvements in Adjustable Pipe-Wrenches, (for which I have filed application in Great Britain July 24, 1917, under No. 111,983,) of which 10 the following is a specification.

This invention relates to improvements in adjustable pipe wrenches, which improvements comprise a means whereby in operation the pipes or the like of various diameters are gripped by the wrench at three points, which three point grip is obtained by the combination with a pair of pivoted jaws, each having a gripping face, of an attachment having a gripping face, one part 20 of which attachment is secured at the point of the pivot, and the other part to one of the jaws.

By such an attachment the wrench can be adjusted so as to utilize the three point grip 25 in respect of an extended range of sizes of pipes, and the like, and can also be adjusted to obtain such three point grip on pipes which are in cramped and awkward positions not readily accessible with ordinary 30 pipe wrenches.

In order that this invention may be clearly understood and readily carried into practice, reference may be had to the appended explanatory sheet of drawings, upon which:—

35 Figure 1 is a front elevation of the wrench when in position for operating upon an article of small diameter.

Fig. 2 is a side elevation of Fig. 1.

40 Fig. 3 is a similar elevation of the grip part of the wrench to that of Fig. 1, but illustrating the jaws when operating upon an article of larger diameter.

Fig. 4 is a similar elevation to Fig. 2, but 45 illustrating an adjustment of the pivot of the jaws to allow of articles of still larger diameter being gripped.

Fig. 5 is a similar elevation to Fig. 1, but illustrating another position of adjustment of the various parts.

50 In an embodiment of this invention the wrench is comprised of the two jaws *a* and *b* having the handle lever extension *a*¹ and *b*¹, provision being made for the jaws *a* and *b* to be pivoted together by a bolt or pin *d*.

55 The jaw *b* is provided with a perforation for

receiving the pin *e*, one end of a quadrant attachment *f* being mounted on the pivot pin *d*, the other end of the attachment being mounted on the pin *e*, in such a manner that the pipe *g* or the like illustrated by dotted lines is gripped at three points, viz. *a*², *b*², and *f*², the serrated faces of the jaws *a* and *b* being so curved that in combination with the curved serrated face of the quadrant attachment *f*, the three point grip comes into 60 operation, whatever the size or diameter of the pipe or the like may be, so long as the size of such pipe or the like is within the compass of the wrench. One end of the quadrant attachment *f* is clamped against 65 the jaw part *a* and secured in position by the nut *d*¹, while the other end is clamped against the jaw part *b* by the milled nut *e*¹, in such a manner that by releasing the nuts *d*¹ and *e*¹ and sliding the quadrant slots 70 *f*¹ into various positions, the serrated or gripping face *f*³ of the quadrant, the curve of which is eccentric to the slot *f*¹, may be adjusted in its position in relation to the 75 serrated curves of the jaws *a* and *b*.

For adjusting the jaw parts *a* and *b* so as to operate upon pipes or the like of a larger diameter or size, the pivot pin *d* is inserted in an aperture *b*³ which is provided in the jaw part *b*, the quadrant *f* being secured in 80 position by the milled nut *d*¹ on the pivot pin *d* at the one end, and the nut *e*¹ on the pin at the other end as shown in Fig. 4, where an example of the gripping of a larger pipe *g*¹ is illustrated by dotted lines.

In cases where it is required to grip the pipe as close to the outside of the mouth of the jaws *a* and *b* as possible, the pin *e* may be inserted in the aperture *b*⁴, the one end of the quadrant attachment *f* being then secured in the position shown by Fig. 5 by the nut *e*¹, the other end being secured in 90 position by the nut *d*¹ by the pivot pin *d*.

What I claim as my invention and desire to secure by Letters Patent is:—

1. A pipe wrench comprising a pair of levers respectively provided with curved inner and outer gripping jaws, a pivot connecting said levers together, a third gripping element extending across the inner end portions of the jaws and having a curved slot in which the said pivot operates, and a pivot connecting said element to the outer jaw and also operating in the said slot.

2. A pipe wrench comprising a pair of

110

levers respectively provided with curved inner and outer gripping jaws, a pivot connecting said levers together, a third gripping element extending across the inner end 5 portions of the jaws and having a curved slot in which the said pivot operates, and a pivot connecting said element to the outer jaw and also operating in the said slot, said

outer jaw having means to enable the last named pivot to be shifted.

In witness whereof I have hereunto set my hand in the presence of two witnesses.

WILLIAM WHELAN.

Witnesses:

ARTHUR H. BROWN,
EDGAR N. WHEELER.
